SCARIFIER MACHINE

George W. Swisher, Jr., Oklahoma City, Don W. Smith,
Edmond, and Gordon L. Spivey, Oklahoma City, Okla.,
assignors to CMI Corp., Oklahoma City, Okla.

Filed Mar. 20, 1969, Ser. No. 16,346

Term of patent 14 years

Int. Cl. D12—09

U.S. Cl. D14—3

FIG. 1 is a fragmentary side view of the novel design;
FIG. 2 is another fragmentary side view of the design;
FIG. 3 is a top view of the design; and
FIG. 4 is a first end view of the design.

The side opposite to that shown and the other end are identical to the side and end shown.

We claim:

The ornamental design for a scarifier machine, as shown and described.
